GEORGE H. MOLDEN, OF BRIDGEPORT, CONNECTICUT.

LOCK.

No. 911,088.

Specification of Letters Patent.

Patented Feb. 2, 1909.

Application filed November 7, 1908. Serial No. 461,573.

To all whom it may concern:

Be it known that I, WALERJAN SZYMANSKI, a citizen of the United States, residing at Bridgeport, county of Fairfield, State of Connecticut, have invented a new and useful 5 Lock, of which the following is a specification.

This invention relates to locks adapted for general use and is illustrated as applied to a trunk lock, and the invention has for its objects to provide a lock so constructed that certain releasing operations must be performed before the bolt can be retracted by rotation of the key and in so constructing the lock that after the releasing operations are 10 performed two rotations of the key are required to retract the bolt, thus rendering it impossible for unauthorized persons to operate the lock, as, when the bolt has been moved to its fully thrown position it can only 15 be retracted by a person who understands the mechanism fully. The lock may, however, if preferred be used as an ordinary lock, that is the bolt when thrown to its primary locking position by a single rotation of the 20 key may be retracted by a single reverse rotation of the key and without preliminary operations.

With these and other objects in view the invention consists in certain constructions 25 and in certain parts, improvements and combinations which will be hereinafter described and then specifically pointed out in the claims hereunto appended.

In the accompanying drawings forming a 30 part of this specification, Figure 1 is a front elevation of my novel lock showing the hasp in the locked position; Fig. 2 a section on the line 2—2 in Fig. 1 looking in the direction of the arrows; Fig. 3 an elevation of the lock reversed; Fig. 4 an elevation as seen 35 from the back in Fig. 1 with the back and intermediate plates removed, the bolt being in the secondary or fully thrown position; Fig. 5 a similar view with the tumblers removed, 40 showing the dog; Fig. 6 a similar view with the dog removed; Fig. 7 a section of the face plate on the line 7—7 in Fig. 4 looking in the direction of the arrows, the mechanism of the lock appearing in end elevation; Fig. 8 a 45 similar section on the line 8—8 in Fig. 5, looking in the direction of the arrows; and Fig. 9 is a view of the dog detached.

10 denotes the face plate, 11 the back plate, 12 shouldered studs separating the 50 plates, 13 a hasp which is provided with a

keeper 14 through which the bolt passes, 15 the key-hole, 16 the key post and 17 an escutcheon plate surrounding the key hole which may or may not be used, as preferred. I preferably, however, use the escutcheon 60 plate and provide it with raised bosses or projections 18 as it imparts an ornamental appearance to the lock and the projections thereon correspond with the releasing plate, presently to be described, and make picking 65 of the lock more difficult.

19 denotes the bolt the forward end of which slides through and is retained by a strap 20 which is secured to the inner side of the face plate. The rear end of the bolt is 70 provided with a slot 21 which slides over a stud 22 projecting from the face plate and which acts to limit the movement of the bolt in each direction. The lower edge of the bolt is provided with walls or bearing surfaces 58, 59 and 60. Wall 58 is engaged by 75 the key in its second rotation in unlocking to move the bolt from its primary locking to its secondary or fully thrown position, wall 59 is engaged by the key in its first rotation in 80 locking to move the bolt from its retracted position, indicated by dotted line 56 in Figs. 4, 5 and 6, to its primary locking position, indicated by dotted line 57, and wall 60 is engaged by the key in its second rotation in 85 locking to move the bolt from its primary locking to its secondary or fully thrown position.

24 denotes a dog which is pivoted on a stud 25 projecting from the bolt and extends 90 rearwardly therefrom. This dog is provided with a recess 26 in its lower side to provide clearance for an angular stud 27 which projects from the bolt. The rear end of the dog is provided with a thickened portion, indicated by 28, and said thickened portion is provided with a wall or bearing surface 29 which is engaged by the key in 95 its first rotation in unlocking to return the bolt from its secondary or fully thrown position to its primary locking position, indicated by dotted line 57, with a wall or bearing surface 30 which is engaged by a stud, presently to be described, with an inclined groove 31 which rises from the rear end of 100 the dog and is also engaged by the stud, and with a recess 32 into which said stud passes when the bolt and dog are fully retracted, as will be more fully explained.

43 denotes a spring secured to the bolt as 110

at 44, which bears against the dog and acts to retain it in operative position.

33 denotes tumblers—four in the present instance—which are pivoted on a stud 34 extending inward from the face plate and are provided with slots 35 through which stud 27 on the bolt extends.

36, 37 and 38 denote angular recesses in the tumblers which open into the slots and 10 are adapted to receive angular stud 27 to lock the bolt in the retracted and in the primary and secondary locking positions. The tumblers are retained in engagement with the stud by means of springs 39, one 15 end of each spring engaging a tumbler and the other end bearing against a stud 40 which projects inward from the face plate. The opposite sides of slots 35 are provided with recesses 41 corresponding with recesses 36, 20 37 and 38, which are adapted to receive stud 27 and to prevent retraction of the bolt when attempt is made to pick the lock with a false key.

42 denotes the engaging walls or surfaces 25 of the tumblers which are normally out of alignment with each other and require variant bits upon the key to place the slots and recesses in the tumblers in alignment. As this construction is common in locks, the 30 tumblers are shown only in superposed position and illustration of the different engaging walls is omitted.

An important feature of the present invention is that when the bolt is in the secondary or fully thrown position it is not 35 subject to control by the key until two preliminary releasing operations have been performed, which I will now describe. The back plate, which carries the key post and 40 two studs, is made to yield outward. Between the back plate and the shouldered studs is an intermediate plate 45 which performs the usual functions of a back plate in retaining the parts of the lock in place and 45 permits back plate 11 to have a spring action independent of the intermediate plate. The key post 16 projects inward from the back plate and passes through a clearance hole in the intermediate plate.

50 46 denotes a stud also projecting inward from the back plate and extending through a clearance hole in the intermediate plate, which is engaged by the dog as already referred to and as will presently be fully described.

47 denotes a locking stud which projects inward from the back plate and passes through a clearance hole in the intermediate plate and is provided in one side with a recess 48 which is engaged by a locking plate 49 carried by a stud 50 which is adapted to reciprocate in a slot 51 in the face plate. At the outer end of stud 50 is a releasing plate 52 which lies on the outer side of the face 55 plate, or the outer side of the escutcheon

plate if used, and serves as a finger-piece to move locking plate 49 out of the engaging position. A block 53 carried by a spring 54 bears against stud 50 and acts to normally retain the locking plate in the engaging position. Spring 54 is shown as secured to a stud 55 projecting inward from the face plate. The outer ends of the shouldered studs are threaded and are engaged by nuts 61. The nuts upon the lower studs (see 75 Fig. 3) lie upon the outer side of the back plate and clamp both back and intermediate plates tightly to the shoulders upon the studs. At the upper end of the back plate are clearance recesses 62 in which the upper 80 nuts lie, said upper nuts locking the intermediate plate rigidly to the studs but leaving the upper end of the back plate free so that it may spring from its attached lower end.

The operation is as follows: As has been 85 stated, my novel lock is adapted, if preferred, to be used as an ordinary lock; that is, the bolt may be thrown to the primary locking position by a single rotation of the key and may be retracted by a reverse rotation of the 90 key. The essential features of novelty in the lock, however, are that the bolt may be thrown farther forward past the primary locking position by a second rotation of the key and when thrown to this secondary 95 position can only be returned to the retracted position by two reverse rotations of the key, and furthermore that while the key can be rotated freely in either direction there will be no movement whatever of the bolt 100 toward the retracted position until two preliminary operations have been performed in proper sequence. In all the figures of the drawings the parts are shown in full lines in the fully locked position, other positions of 105 the dog being indicated by dotted lines. When the bolt is fully thrown, that is by two rotations of the key, all of the parts are in the position shown in full lines in Figs. 4 and 7. Stud 27 upon the bolt is in engagement 110 with recesses 36 in the tumblers, the dog is locked out of operative position by the engagement of wall 30 with stud 46, and the back plate and the intermediate plate are 115 locked together by the engagement of locking plate 49 with the recess in stud 47. Before the bolt can be retracted it is necessary to unlock the back plate from the intermediate plate so that the back plate can be sprung outward (see dotted lines Fig. 7) and 120 dog 24 released from stud 46. The first operation that must be performed preliminary to retracting the bolt is to move releasing plate 52 (see Fig. 1) toward the left. This moves locking plate 49, as seen in Fig. 4, 125 toward the right against the power of spring 54 and leaves locking stud 47 released. The operator still holding plate 52 toward the left as seen in Fig. 1, with the key, a nail or any suitable implement, presses inward upon 130

key post 16. This springs the back plate outward (see Fig. 7), the pressure on the key post being continued until stud 46 is forced backward (toward the front as seen in Fig. 4) far enough to release dog 24, which is then forced by spring 43 under the stud to the position shown in dotted lines in Fig. 5. The movement of the dog is limited by the engagement of the wall of clearance recess 26 in the dog with stud 27 on the bolt, and in the released position of the dog the stud will be over inclined groove 31 and will drop into said groove when the back plate is released. The position of stud 46 relatively to the dog 15 before and after the dog is released, by forcing the outer plate which carries the stud outward by pressure on the key post, will be readily understood by comparing Figs. 4 and 5 in which the stud is shown in section with Figs. 7 and 8. As soon as the dog has been 20 swung under the stud by spring 43, which will be known by a slight click when the dog engages stud 27, the operator relieves the pressure on the key post which is returned to its normal position by the resiliency of the 25 back plate and releases plate 52 which returns to its normal position, spring 54 and block 53 carrying the locking plate into engagement with the recess in the locking stud 30 and locking the upper end of the back plate to the intermediate plate. The operator then places the key (not shown) upon the key post and turns the key toward the left, as seen in Fig. 4, to retract the bolt. The 35 bits of the key engage the tumblers and raise them, releasing stud 27 from recesses 36 and leaving the stud central in slots 35 in the tumblers. Another portion of the key engages wall 29 on the dog and moves the dog 40 and with it the bolt from the secondary or fully thrown position toward the left as seen in Figs. 4 and 5, leaving it at the primary locking position indicated by the dotted line 45 57, the bolt being still entirely through the keeper. It should be understood that prior to the release of the dog and its movement from the full line to the dotted position, indicated by 57, the key may be rotated freely in either direction and will raise the tumblers 50 but will have no effect on the bolt as no portion of the bolt or the dog carried thereby is now in position to be engaged by the key. In case of an attempt to pick the lock by means of a false key, some of the recesses 55 57 in the tumblers are likely to be engaged by stud 27 thereby locking the bolt against movement in either direction. After the first rotation of the key, wall 58 on the bolt will be in approximately the dotted position 60 of wall 29 upon the dog in Fig. 5 and will be engaged by the key during its second rotation, the effect of which will be to raise the tumblers as before, leaving stud 27 in slots 35 and to move the bolt from the dotted position, indicated by 57 in Figs. 4, 5 and 6, to

the dotted position, indicated by 56, which is the fully retracted position.

As has already been explained and is shown in Fig. 5, in the released or unlocking position of the dog, stud 46 will be in engagement with inclined groove 31. When the bolt and dog are moved backward from the secondary or fully thrown position to the primary locking position, indicated by the dotted line 57, the stud will ride up the incline, and when the bolt and dog are moved from the primary locking to the retracted position, indicated by the dotted line 56, the stud will pass off from the dog and will drop into recess 32 therein. When the bolt is in the fully retracted position the dog will be in the position indicated by dotted lines in Fig. 4. When the bolt is moved to either the primary or secondary locking positions, wall 30 of the dog will ride along the stud which will raise the dog as the bolt is moved forward, and in the secondary locking position of the bolt the dog will be in the full line position in Fig. 4 and both dog and bolt will be wholly out of reach of the key. From this position the dog can only be released by inward pressure upon the key post after the yielding back plate has been unlocked. If it is desired to use the lock as an ordinary lock, the bolt may be thrown to the primary locking position, that is to the dotted position indicated by 57, by a single rotation of the key and may be retracted by a single reverse rotation of the key. Should it be required, however, to make retraction of the bolt as difficult as possible, the bolt is thrown from the primary locking position indicated by dotted line 57 to the secondary or fully thrown position, as in full lines in Figs. 4, 5 and 6, by an additional rotation of the key. From this position, as already stated, the bolt can only be retracted by first moving plate 52 to unlock the outer plate and then springing the outer plate outward by pressure on the key post to release the dog and then inserting the proper key and giving it two reverse rotations.

Having thus described my invention, I claim:

1. In a lock, the combination with a bolt having walls for successive engagement by a key in throwing the bolt and a wall for engagement by a key in retracting the bolt, of a dog pivoted to the bolt and having a wall for engagement by the key in the first movement of retracting the bolt, and means for retaining the dog out of operative position so that operation of the key will have no effect on the bolt.

2. In a lock, the combination with a bolt having walls for successive engagement by a key in throwing the bolt and a wall for engagement by the key in retracting the bolt, of a dog pivoted to the bolt and having a wall for engagement by the key in the first move-

- ment of retracting the bolt, a yielding back plate and a stud carried by the back plate by which the dog is retained out of operative position when the bolt is fully thrown, so 5 that the bolt cannot be retracted.
3. In a lock, the combination with a bolt having walls for successive engagement by a key in throwing the bolt and a wall for engagement by the key in retracting the bolt, 10 of a dog pivoted to the bolt and having a wall for engagement by the key in the first movement of retracting the bolt, a yielding back plate, a stud carried by said plate by which the dog is retained out of operative 15 position when the bolt is fully thrown, and means for locking the back plate against movement.
4. In a lock, the combination with a bolt having walls for successive engagement by a key in throwing the bolt and a wall for engagement by the key in retracting the bolt, of a dog pivoted to the bolt and having a wall for engagement by the key in the first movement of retracting the bolt, a yielding 20 back plate, a stud carried by said plate by which the dog is retained out of operative position when the bolt is fully thrown, a locking stud carried by said plate, a locking plate engaging said stud to lock the back plate 25 against movement and means for actuating the locking plate from outside the lock to release the back plate.
5. In a lock, the combination with a bolt having walls for successive engagement by a key in throwing the bolt and a wall for engagement by the key in retracting the bolt, of a dog pivoted to the bolt and having a wall for engagement by the key in the first movement of retracting the bolt, a yielding 30 back plate carrying a stud by which the dog is retained out of operative position when the bolt is fully thrown and a stud having a locking recess, a spring-controlled plate engaging said recess to lock the back plate against 35 movement and means for controlling the locking plate from outside the lock.
6. In a lock, the combination with a bolt having walls for successive engagement by a key in throwing the bolt and a wall for engagement by the key in retracting the bolt, of a dog pivoted to the bolt and having a wall for engagement by the key in the first movement of retracting the bolt, a yielding back plate, a stud carried by said plate by 40 which the dog is retained out of operative position when the bolt is fully thrown, means for locking the back plate against movement and means for releasing the dog when the back plate is released.
7. In a lock, the combination with a bolt having walls for successive engagement by a key in throwing the bolt and a wall for engagement by the key in retracting the bolt, of a dog pivoted to the bolt and having a wall for engagement by the key in the first 45 movement of retracting the bolt, a yielding back plate carrying a stud by which the dog is retained out of operative position when the bolt is fully thrown, a locking stud and a key post, a spring-controlled locking plate engaging the locking stud to lock the back plate against movement, a releasing plate on the outer side of the lock and a connection between the releasing plate and the locking plate, pressure on the key post when the back plate is released acting to spring the back plate and release the dog.
8. In a lock, the combination with a bolt having walls for successive engagement by a key in throwing the bolt, and a wall for engagement by the key in retracting the bolt, of a spring-controlled dog pivoted to the bolt and having a wall for engagement by the key in the first movement of retracting the bolt, a yielding back plate carrying a stud by which the dog is retained out of operative position when the bolt is fully thrown, and a key post and means controlled from the outer side of the lock for locking the back plate against movement, pressure on the key post when the back plate is released acting to spring the back plate and release the dog which moves into position to permit retraction of the bolt by a key.
9. In a lock, the combination with a bolt having walls for successive engagement by a key in throwing the bolt and a wall for engagement by a key in retracting the bolt, of a dog pivoted to the bolt and having a wall for engagement by the key in the first movement of retracting the bolt, a wall adapted to engage a stud for the purpose set forth, and an inclined groove rising from the rear end thereof and a yielding back plate carrying a stud which in the fully thrown position of the bolt retains the dog out of operative position, said stud releasing the dog when the back plate is swung outward and riding up the incline of the slot and then off from the dog when the bolt is retracted, the throwing of the bolt causing the dog to be again raised by the stud out of operative position.
10. In a lock, the combination with a bolt having walls for successive engagement by a key in throwing the bolt and a wall for engagement by a key in retracting the bolt, of a spring-controlled dog pivoted to the bolt and having a wall for engagement by the key in the first movement of retracting the bolt, a wall, an inclined groove rising from the rear end thereof and a recess in one side and a yielding back plate carrying a stud which in the fully thrown position of the bolt is engaged by wall 30 to retain the dog out of operative position, said stud releasing the dog when the back plate is sprung outward and then riding up the incline of the slot and into the recess when the bolt is retracted.
11. In a lock, the combination with a bolt having walls for successive engagement by a

key in throwing the bolt and a wall for engagement by a key in retracting the bolt, of a dog pivoted to the bolt and having a wall for engagement by the key in the first movement of retracting the bolt, another wall adapted to engage a stud for the purpose set forth, and an inclined groove rising from the rear end thereof, a yielding back plate carrying a stud which in the fully thrown position of the bolt retains the dog out of operative position, and means for locking the back plate against movement, outward movement of the back plate when released causing the stud to release the dog.

12. In a lock, the combination with a bolt having walls for successive engagement by a key in throwing the bolt and a wall for engagement by a key in retracting the bolt, of a dog pivoted to the bolt and having a wall for engagement by the key in the first movement of retracting the bolt, another wall adapted to engage a stud for the purpose set forth, and an inclined groove rising from the rear end thereof, a yielding back plate carrying a stud which in the fully thrown position of the bolt retains the dog out of operative position and a key post, and means for locking the back plate against movement, pressure on the key post when the back plate is released causing the stud to release the dog.

13. In a lock, the combination with a face plate, shouldered studs projecting therefrom and intermediate and back plates secured to said studs, one end of the back plate being left unattached and free to yield, of a bolt having walls for successive engagement by a

key in throwing the bolt and a wall for engagement by the key in retracting the bolt, a dog pivoted to the bolt and having a wall for engagement by the key in the first movement of retracting the bolt, a stud carried by the back plate by which the dog is retained out of operative position when the bolt is fully thrown, and means for locking the back plate against movement, pressure on the back plate when released causing the stud to release the dog.

14. In a lock, the combination with a bolt having walls for successive engagement by a key in throwing the bolt, a wall for engagement by the key in retracting the bolt, and a stud 27, of a dog pivoted to the bolt and having a wall for engagement by the key in the first movement of retracting the bolt and tumblers having corresponding longitudinal slots which receive said stud freely, and also having recesses which are engaged by said stud to lock the bolt in the retracted and in the primary and secondary locking positions, a yielding back plate carrying a stud 46 by which the dog is held out of operative position when the bolt is fully thrown and means for locking the back plate against movement, pressure on the back plate when it is released causing stud 46 to release the dog.

In testimony whereof I affix my signature, in presence of two witnesses.

WALERJAN SZYMANSKI.
